UNITED STATES PATENT OFFICE.

ALDEN C. OLANDER, OF CHICAGO, ILLINOIS.

COIN-OPERATED NERVE AND EYE TESTING MACHINE.

Application filed February 15, 1928. Serial No. 254,582.

My invention relates to devices displayed for public patronage in stores, on train platforms, and the like, and more particularly to such devices as are commonly known as testing machines for strength, skill, and other qualities, and it is my main object to produce a device on the above order which tests the vision and steadiness of the patron.

A further object of the invention is to design the same with an element to receive a projectile, whereby the marksmanship of the patron may be determined to a lesser or greater degree.

A still further object of the invention is to construct the mechanism referred to on adjustable lines, whereby to require more or less skill on the part of the operator.

Another object of the invention is to design the same on the order of a stand suitable for a counter, showcase, or shelf, and with visual characteristics imparting an air of mystery.

An essential object of the invention is to provide therein a guard to prevent the unauthorized removal of the projectile, which latter may be of valuable or monetary character.

A final, but nevertheless important object of the invention is to construct the novel appliance on simple lines, so that it may be produced at low cost, operated with ease, and maintained without appreciable repair for long periods.

With the above objects in view and any others that may suggest themselves in the specification and claims to follow, a better understanding of the invention may be gained by reference to the accompanying drawing, in which—

40. Figure 1 is an elevation of the novel device, with a column element partly broken away on account of limited space;

Fig. 2 is an interior view of the device from the front;

45. Fig. 3 is a plan view; and

Fig. 4 is a vertical cross section.

Referring specifically to the drawing, 10 denotes the housing for the novel device, the same being generally square although its shape is immaterial. The housing is provided with a lid 11, which carries a lock 12 to secure it to the housing, and the lid is equipped with rubber feet 13 in order that the device may not mar the surface upon which it is placed. The housing is intended to receive tokens or coins, in view of which

I provide the lock 12 in order that the lid may not be opened by an unauthorized person to remove the tokens or coins.

The top of the housing is formed with 60 a central opening from which rises a tubular column 14 of glass. The object of the column is to form a receiver, into which a token or coin is dropped by the patron, the transparency of the column serving to make 65 the path of the token or coin visible to him.

At the base of the column 14 is a funnel-like receptacle 15 of elongated cross section, which is extended downwardly to form a chute 16, the latter emerging from the front 70 of the housing in open form as indicated at 17. The funnel-like receptacle 15 is directly in the center of the column 14 and may receive the token or coin if dropped centrally, causing the same to roll down the 75 chute 16 and be delivered at the open end 17 for removal by the entrant.

The top of the housing 10 receives a shelf 18 which supports a dome-like shell 19 about the element 15, the shell being somewhat 80 smaller in diameter than the column and rigid. Within the shell are mounted a pair of substantially semispherical cups 20 pivoted upon pins 21 at opposite sides of the shell 19 and having extensions 22 projecting 85 downwardly. Thus, upon moving the stems, the cups 20 may be rocked so that their supporting edges 20^a approach or recede from each other to limit the space immediately above the funnel element 15. 90 Thus, if a token or coin is dropped with exacting skill, when the edges 20^a are fairly close together, the coin will fall into the funnel element 15 and be delivered to the entrant; however, should the coin strike 95 laterally of this site, it would slide down along the outside of the shell 19 and drop into the housing. Thus, the further the edges 20^a of the cups 20 are spaced, the greater the chance for a skillfully dropped coin to be received into the chute and returned, pointing to the fact that the device

only charges for its service when the entrant fails to exercise the proper amount of skill consistent with the spacing of the cups. 100

The cups are rocked by the manipulation of dials 23 on the front of the device, these dials operating shafts 24 on which are mounted pinions 25. The pinions are in mesh with rack bars 26 which are connected 110 to the stems 22 of the respective cups 20 in a manner to cause either cup to move in the

closing direction when the corresponding dial is turned to suit. Thus, to close the right-hand cup 20, the natural inclination would be to turn the right-hand dial in a counter-clockwise direction, consistent with which the gearing is arranged. The dials are equipped with finger knobs 23^a, and the rack bars 26 rest on rollers 27 rotatable on rods 28 carried in the housing. Below the column 14 I have provided an inverted hood 29 to serve as a guard. This hood is spaced sufficiently below the shell 19 to permit tokens and coins sliding down outside of the latter to gather toward the center, and drop into the housing. However, the center portion of the hood is sufficiently close to the chute 16 to deflect any tokens or coins in the housing which may collect at the particular site when the housing is inverted with the intention of unauthorizedly removing the earned contents thereof. It will be seen that this could be done by securing the passage of the tokens or coins next outside the shell 19; however, the hood 29 acts as a bar to such an operation, deflecting the tokens or coins outwardly to remain in the housing. If any coin should find its way into the hood when the housing is inverted by way of the space between the hood and the chute 16, it would be a rare occurrence and of a negligible character.

It will be seen that the novel device may be employed as a nerve and eye tester. Entrants would be obliged to use good eye sight and a steady hand to drop a given token or coin to advantage, and contests could be had between entrants by also employing a spacing gauge in the form of the cups 20. In this connection, the dials 23 may be inscribed with figures characteristic of the spacing values of the cups, so that one may determine the degree of his skill, vision or steadiness. The device as seen from the front gives, through the presence of the dials 23, the impression of a calculating machine or a scientific meter; and I choose to tint the upper portion of the glass column 14 with a translucent or deep color, so that at first sight the device will impart an air of mystery as a matter of attraction. As is clearly evident from the construction, few and simple parts are employed, no delicate clockwork or other mechanism is necessary and it is easily possible to produce the device at small cost while constructing the same for efficient operation and durability during long use.

While I have illustrated and described the invention in the preferred form, it will be evident that the same is capable of many minor changes and refinements and it is my intention to claim such changes and refine-

ments as coming within the spirit and scope of the appended claims.

I claim:

1. A skill testing appliance comprising an upright casing defining a passage through which a projectile may be dropped, a housing at the base of said upright casing having a target aperture formed with coacting sections, and manually operable means to vary the size of said aperture.

2. A skill testing appliance comprising an upright casing defining a passage through which a projectile may be dropped, a housing at the base of said upright casing having a target aperture formed with coacting sections, and manually operable means to vary the size of said aperture sections, gearing for operating said sections, and manually operable means exteriorly of the housing for controlling said gearing.

3. A skill testing appliance comprising an upright casing defining a passage through which a projectile may be dropped, a housing at the base of said upright casing having a target aperture formed with coacting sections, and manually operable means to vary the size of said aperture sections, gearing for operating said sections, and manually operable means exteriorly of the housing for controlling said gearing comprising handles operable in directions harmonious with said sections.

4. A skill testing appliance comprising an upright casing defining a passage through which a projectile may be dropped, a housing having an opening communicating with the lower end of the upright casing, pivoted jaws adjacent the lower end of the upright casing movable to define a target aperture of varying size, and a chute having its outer end extending exteriorly of the housing and having its inner end disposed in upright position beneath said jaws in a manner to receive a projectile passing through said target aperture.

5. A skill testing appliance comprising an upright casing defining a passage through which a projectile may be dropped, a housing having an opening communicating with the lower end of the upright casing, pivoted jaws adjacent the lower end of the upright casing movable to define a target aperture of varying size, and a chute having its outer end extending exteriorly of the housing and having its inner end disposed in upright position beneath said jaws in a manner to receive a projectile passing through said target aperture and a shell fitted over said jaws and provided with a fixed aperture.

In testimony whereof I affix my signature.

ALDEN C. OLANDER.
